(57) **CLAIM**

The ornamental design for a fruit ripening container as shown and described.

DESCRIPTION

FIG. 1 is a front top perspective view of a fruit ripening container showing our new design;

FIG. 2 is a front elevation view thereof;

FIG. 3 is a rear elevation view thereof;

FIG. 4 is a left-side view thereof;

FIG. 5 is a right-side view thereof;

FIG. 6 is a top view thereof;

FIG. 7 is a bottom view thereof; and,

FIG. 8 is another perspective view showing the fruit ripening container in use.

The broken lines illustrate environmental subject matter only and form no part of the claimed design.

1 Claim, 4 Drawing Sheets
